Term of patent 7 years

(Cl. D14—3)

Fig. 2

To all whom it may concern:

Be it known that I, Kenneth Lyle Kamp, a citizen of the United States, residing at Norwood, Hamilton County, State of Ohio, have invented a new, original, and ornamental Design for an Automobile, of which the following is a specification, reference being had to the accompanying drawings, forming a part thereof.

In the drawings:

Fig. 1 is a view in side elevation of the automobile showing my new design;

Fig. 2 is a view in perspective showing the rear and one side of the automobile; and

Fig. 3 is a view in perspective showing the front and one side of the automobile.

The dominant feature of the design resides in the full line portion of the drawing.

I claim:

The ornamental design for an automobile, as shown and described.
